FOOT FIN FOR SWIMMERS

Everett A. Brunner, 3807 N. Merced,
Baldwin Park, Calif.

Filed Nov. 2, 1964, Ser. No. 82,441

Term of patent 14 years

(Cl. D71—1)

I claim:

The ornamental design for a foot fin for swimmers, as shown.
